CLAIM

(52) **U.S. Cl.**

The ornamental design for a manifold engagement portion of a filter cartridge, as shown and described.

USPC **D23/209**

DESCRIPTION

(58) **Field of Classification Search**

FIG. 1 is top, front, and right-side perspective view of a manifold engagement portion of a filter cartridge; FIG. 2 is a right-side elevation view of a manifold engagement portion of a filter cartridge shown in FIG. 1; FIG. 3 is a front elevation view of a manifold engagement portion of a filter cartridge shown in FIG. 1; FIG. 4 is top view of a manifold engagement portion of a filter cartridge shown in FIG. 1; and, FIG. 5 is a bottom view of a manifold engagement portion of a filter cartridge shown in FIG. 1.

USPC D23/213, 207, 209; 210/232, 234, 236,

210/493.2; 285/360, 361

CPC B01D 35/30; B01D 35/153; B01D 35/157

See application file for complete search history.

(56) **References Cited**

The left-side and rear elevation views of the manifold engagement portion of a filter cartridge are substantially the same as the right-side and front views, respectively. The broken lines in FIGS. 1-5 are for the purpose of illustrating environmental structure and form no part of the claimed design thereof.
